UNITED STATES PATENT OFFICE.

RALPH R. ROOT, OF CLEVELAND, OHIO.

MASSAGING INSTRUMENT.

1,325,332.

Specification of Letters Patent. Patented Dec. 16, 1919.

Application filed April 17, 1916. Serial No. 91,506.

To all whom it may concern:

Be it known that I, RALPH R. Root, a citizen of the United States, residing at Cleveland, in the county of Cuyahoga and State of Ohio, have invented a certain new and useful Improvement in Massaging Instruments, of which the following is a full, clear, and exact description.

This invention relates to an electrical 10 massage device in which a vibrating movement is given to a massaging implement.

The object of the invention is to produce a device of the character indicated, which is simple in construction, has a low cost 15 of manufacture and is efficient for the purpose for which it is intended.

Generally speaking, the invention comprises the elements and combinations thereof set forth in the accompanying claims.

Reference should be had to the accompanying drawings forming a part of this specification, in which Figure 1 is a side elevation of the device; Fig. 2 is an elevation with portions in section; Fig. 3 is an elevation of the device with the cover removed; Fig. 4 is a section of the device; Fig. 5 is a top plan view with parts removed, the casing being shown in section; Fig. 6 is a transverse section of the device; Fig. 7 is a top plan view with portions in section showing a part of the device; Fig. 8 is a fragmentary illustration in elevation of a portion of the device; and Fig. 9 is a section of a detail of the construction.

In massage instruments it is desired to give to the massage implement a vibratory movement. Different characters of vibratory movement may be given to the massaging implement, but in the present instance the vibration is a simple back and forth vibratory movement.

It has been usual heretofore, to construct electrical vibrators, using an electric motor for furnishing the motive power, by which 45 the massage instrument is operated. In the present instance the motive power is furnished by the vibrating armature of an electromagnet.

In the drawings, 1 represents the massage 50 implement, the particular one shown being of a usual and well known form, but the particular form is not at all essential to the present invention. This massage implement is secured to an armature 2, which 55 armature has a portion that extends slightly forward and has a screw-threaded portion

adapted to receive the threaded shank of the member 1.

The armature 2 co-operates with an electromagnet, the windings of which are represented at 3 and the core of which is represented at 4. The core of the electromagnet is made up of laminations which are suitably secured together. Each lamination is preferably a stamping and assumes the form 60 indicated at 4^a in Fig. 4, that is to say, each stamping comprises a central part 4^b and side members 4^c which are joined to the middle portion 4^b.

These members are assembled and held 70 in definite relationship to each other by a holding member 6, such as shown in Figs. 7 and 9. This holding member is provided with a central opening 6^a which extends over the central portion 4^b of a number 75 of laminations, and a suitable number of laminations are employed to snugly fit within the opening 6^a. This member 6 not only serves to hold these members together at the lower portion, but also serves as a means 80 for fastening to the base of the device, which may be accomplished in any suitable manner as by means of screws 6^b.

Around the central portion 4^b and between the side portions 4^c of the laminated core, is 85 wound the coil 7. This coil is of usual construction and as in its winding, it extends well up along the central portion 4^b of each lamination, it serves to hold the laminations together.

The coil is in a measure held in place by a disk 8, which disk is preferably of an insulating material and extends beyond the core proper and thus spaces the core from the shell 10 which incases the structure. 95 This then prevents any touching of the core by the casing and prevents any short-circuit through the casing.

The armature 2 lies above the core and it is held in place by the side members 4^c of 100 the end laminations at both ends of the core, which side pieces extend above the other side pieces of the core and are bent inwardly, as indicated at 4^d in Figs. 3 and 4. These pieces 4^d are so arranged that the 105 armature 2 may easily fit beneath the turned in portions. Preferably, although not necessarily, I will make the distance between the tops of the core laminations and the turned in portion 4^d, which comes at the end 110 of the armature which is opposite to that which carries the massage instrument,

slightly less than that between the top of the core and the members 4^a at that end of the armature which carries the massage instrument, this being for the purpose of confining in a larger degree the movement of the armature to that end of the armature which carries the vibrating instrument, thus giving the particular end of the armature in question the maximum amount of movement possible.

- It will be seen that the amount of movement which may be imparted to the armature, is limited for the strength and force of this movement is dependent upon keeping the armature even in its extreme position quite close to the core, so that as the flux builds up when the coil is energized it will quickly and powerfully act upon the armature.
- 20 To the armature there is secured a spring 9, this spring being held to the armature by means of a screw 9^a and is of such length that it bears upon the inturned portions of the extensions 4^a. This then normally holds the armature in contact with the turned in portions of the extensions 4^a, and it is against the action of this spring, that the pull of the flux set up by the coil, works.

All the operating parts, except the massage implement, are housed within a casing 10 and the casing and works are secured to an insulated base 11 through which run the conductors 12 for conducting current to the electromagnet.

35 In the forms shown here, the magnet is intended to be used in connection with an alternating current, so that the electromagnet is energized and deenergized with the reversals of the alternating current. It is for this reason that the core of the electromagnet is laminated.

In operation, the coil of the electromagnet is rapidly energized and deenergized. The usual alternating current circuit, especially in the cities, is usually 60 cycle so that there are 120 reversals in a minute. This means, therefore, that with such a current there would be 120 reversals of the armature 2. It will be seen that the armature 2 will have a very rapid vibrating movement.

As heretofore suggested, it is desirable to confine the major portion of the movement to the end of the instrument which carries the massaging device, inasmuch as such an

arrangement insures that the armature 2 will move its maximum amount each time at that portion which carries the massage implement.

Obviously, at the time of reversal of the energizing alternating current, the electromagnet is demagnetized and the spring 9 retracts the armature.

Having thus described my invention, what I claim is:

1. In a device of the character described, the combination with an implement, an electromagnet comprising an armature to which the said implement is directly attached, a core and an energizing winding which cooperates with the armature, stop members located above the armature with which the ends of the armature are adapted to engage, a spring member secured to the armature and normally holding the armature against the stop members, the said spring and stop members forming the only mounting for the armature.

2. In a device of the character described, the combination with an implement, an electromagnet comprising an armature to which the said implement is directly attached, a core and energizing winding which cooperates with the armature, stop members against which the armature is adapted to bear, a spring normally holding the armature against the stop member, the said spring and stop members forming the only mounting for the armature, the stop members adjacent one end of the armature being positioned to allow a little more movement to the armature as it is attracted by the electromagnet, than is allowed the other end of the armature.

3. In a device of the character described, the combination with an implement, an electromagnet comprising an armature to which the said implement is directly attached, a core and an energizing winding which cooperates with the armature, stop members having inturned portions which engage with the armature and limit the outward movement of the armature, a spring member secured at its middle portion to the armature, the end portions of said spring bearing upon the inturned stop members.

In testimony whereof, I hereunto affix my signature.

RALPH R. ROOT.
